ATTORNEYS

UNITED STATES PATENT OFFICE.

JOHN T. TULLIS, OF HOPE, ARKANSAS, ASSIGNOR TO CHARLES ABER, OF HOPE, ARKANSAS.

CLOTH-CUTTING DEVICE.

Application filed November 12, 1923. Serial No. 674,163.

My invention relates to the art of cloth cutting devices and particularly to such as are adapted for continuous, rapid and accurate, functioning, as required in business houses.

The object of my invention is to provide a device of this character which will be simple, strong and durable, in construction, and which will be positive in its satisfactory operation. I have ascertained by many and divers experiments that a device of this character employing a knife, or razor blade, has a tendency to push the fabric of a soft material, and rather bunch it before cutting, with the result the cloth is cut an irregular manner (sometimes minute and hard to detect with the naked eye) which makes it more liable to ravel out, and is generally unsatisfactory. If the knife becomes dull the irregular cutting is much more pronounced, and if too dull it may refuse, entirely, to function.

For this reason I have adopted the shear cutting method and have incorporated it in a mechanically operated device which provides for the steady and sure closing of the jaws to produce the cut and the accelerated movement in quickly snapping open the jaws in readiness for the succeeding cut. I have also provided mechanism whereby the cut is produced sufficiently far in advance of the fulcrum point of the shears as to enable the shears to be open and ready to cut again before, in the regular forward movement of the cutting device, the cutting jaws reach that point in the cloth which has already been cut. This avoids the jamming of the opening, or nonoperating, shear jaws against the uncut cloth before the cutting operation begins.

Another object of my invention is to provide for the return movement of the cutting device to the starting point—or to any point reached by a rearward movement—without the shear jaws opening and closing during the movement.

My device is particularly adapted for incorporation in cloth measuring devices, such as disclosed in my Patent No. 1238961, issued September 4th 1917 and also my Patent No. 1345811, issued July 6th 1920, but it is equally efficient and adapted for cutting irrespective of cloth measuring machines.

I desire to be protected in the construc-

tion of the cutting device, per se, and for that reason I have illustrated, and will describe, a preferred form of construction. It will, obviously, be understood the disclosure in the drawings herein is simply a preferred form of construction and I do not desire to be limited in the scope of my protection except as defined by the claims appended to this application.

My invention consists of certain details of construction hereinafter set forth, pointed out in my claims, and illustrated in the accompanying drawings, in which Figure 1 shows a cross sectional view of my device fitted to a cloth handling machine;

Fig. 2 shows an elevation view of the same, a portion of the cloth handling machine being broken away to disclose the cutting device;

Fig. 3 shows an enlarged detail view of my cutting device; and

Fig. 4 shows a detail view of the ratchet and pawl mechanism.

Referring to the accompanying drawings the reference numeral 10 is used, generally, to indicate a cloth measuring machine of the type illustrated in my former patents, heretofore referred to, to which is fitted, and secured, my cutting device consisting of a track 11 flanged at 12 and 13 to overlap, so as to permit longitudinal movement therein, a carrier 14, provided with a train of gears, 15 and 16, designed to operate by engagement of one of the gears (15) with a rack 17, secured in the track. The construction is such that the flanges 12 and 13, engaging the upper surface of the carrier 14, hold the gear 15 always in mesh with the rack 17.

The lower blade 18, of the shear jaws, is permanently fixed, and immovable, in its relation to the carrier, and is so mounted that it underlies the cloth to be cut. The upper blade 19, is fulcrumed with the lower blade at 20 and has a lever end 21 extending rearwardly therefrom, said lever end being provided with a slot 22. The small gear wheel 16 is journaled in the carrier and meshes with the larger gear wheel 15, also journaled in the carrier, this gear, as before stated, also being in mesh with, and riding upon, the rack 17. By this construction it is obvious that any movement, either forward or backward, of the carrier will rotate

the gears. To the gear 16 is rigidly secured a ratchet wheel 23, and its pawl 24 is secured to the end of a lever 25, loosely fulcrumed, preferably, to the central point of the ratchet wheel, the other end of said lever 25 terminating in an arm 26, which rides in the slot 22. Preferably, a light spring 27 is secured to the extending end of the pawl 24, this tending to hold the pawl in engagement with a ratchet notch in the ratchet wheel, and these notches are so formed that the forward movement of the carrier, rotating the gear 16 and the ratchet wheel, will hold the lever 25 in engagement with the ratchet wheel, thereby rotating the lever with the ratchet wheel, and this in turn (by the engagement of the arm 26 with the lever 21 through the medium of the slot 22) rotating the arm. This action causes the upper cutting blade 19 of the shears to be operated.

In the rearward movement of the carrier the pawl 24 simply clicks over the ratchet notches, and the lever 21 remains at rest, thus permitting the upper cutting blade 19 of the shears to also remain at rest.

My construction of the parts of the mechanism is such that the cutting distance of the shear jaws is greater than the circumferential distance of the small gear 16, and this functions to produce a long cut in the cloth and snap the upper cutting jaw open again and start it on its downward cutting movement before the cutting jaw has come into contact with the uncut cloth.

The working parts of my cutting device are enclosed in a housing which is designated by the numeral 14, which numeral I have also used as a general indication of the carrier, and the numeral 28 indicates a handle attached to the carrier.

In practical operation to cut a cloth the operator grasps the handle 28 and, the carrier being at its rearward limit of movement, or at a point to the rear of the cloth overlying the lower jaw of the shears, moves the carrier forward in the track. The gear 15, meshing with the rack 17 rotates, thus rotating the gear 16 and the ratchet wheel 23. As by a forward movement of the carrier the pawl 24 is in operative engagement with a notch of the ratchet wheel, the lever 25 will be rotated around its pivotal point (designated by the numeral 29) thus carrying the lever 21 upward and downward (through the medium of the arm, or stud, 26 riding in the slot 22) and this opens and closes the cutting jaw 19 from its fulcrum 20. As before stated, as the circumferential length of the gear 16 is less than the cutting length of the shear jaws, a cut in the cloth will be made and

the upper cutting jaw snapped open and started on its return downward cutting movement before the point of contact of the cutting edges of the upper and lower shear jaws has reached the uncut fabric.

Having thus described my invention what I claim and desire to secure by Letters Patent of the United States, is:

1. A cloth cutting device comprising a carrier mounted, for longitudinal movement, in a track; a pair of shear blades, the bottom blade being secured stationary in the carrier and designed to underlie the cloth to be cut; means whereby the forward movement of the carrier will cause the upper blade to open and close, from its fulcrum point, and the rear movement of the carrier will permit the upper blade to remain in stationary suspended position.

2. A cloth cutting device comprising a track; a carrier mounted for longitudinal movement therein; a rack in said track; a pair of cutting shear blades mounted in said carrier, the lower blade being stationary and the upper blade being fulcrumed thereto; a gear in the carrier to mesh with said rack; a second gear meshing with said first gear; a ratchet on said second gear and a pawl to engage the notches therein; a lever fulcrumed to the central point of said second gear; an arm on said lever designed to engage and ride in a slot in the extended end of the upper cutting jaw of the shears, substantially as shown and described.

3. A cloth cutting device comprising a track; a rack in said track; a carrier to move in said track; a gear journaled in the carrier and meshing with the rack; a pair of cutting blades mounted in said carrier the lower blade being stationary; means whereby the forward movement of the carrier will open and close the upper cutting blade of the shears, and the rearward movement of the carrier will permit the upper blade to remain in the stationary suspended position.

4. A cloth cutting device comprising a track; a rack in said track; a carrier to move in said track; a pair of cutting shear blades in said carrier the lower blade being stationary; a lever, with a slot therein, extending from the fulcrum point of the upper cutting blade of the shears and being rigidly connected therewith; a gear in said carrier to mesh with the rack in the track; a second gear in said carrier in mesh with the first gear; a lever on said second gear and an arm thereon to extend into, and ride within the slot in the aforesaid lever, substantially as shown and described.

JOHN T. TULLIS.
